CLAIM

The ornamental design for a light as shown and described.

DESCRIPTION

FIG. 1 is a perspective view of a light showing our new design;
FIG. 2 is a front view thereof;
FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.
The diagonal shade lines illustrate transparency.
The drawings include surface shading which illustrates contour and not surface ornamentation.

The dot-dash broken lines illustrate boundaries which form no part of the claimed design.

1 Claim, 4 Drawing Sheets
